MAGNETRON

Wilhelm Eberhard Kühle, Dietrich Prinz, and Felix Herriger, Berlin, Germany, assignors to Telefunken Gesellschaft für Drahtlose Telegraphie m. b. H., Berlin, Germany, a corporation of Germany

Application August 20, 1935, Serial No. 36,940
In Germany July 5, 1934

3 Claims. (Cl. 250—27.5)

The invention relates to an electron discharge device for use at high frequencies of the magnetron type, particularly to improvements in the magnetic circuit for such devices.

5 The conventional magnetron tube has an evacuated envelope containing a thermionic cathode and one or more anodes surrounding the cathode. A magnetic field substantially parallel to the cathode is generated by an electro- or permanent 10 magnet. In order to efficiently utilize the magnetic flux to advantage it is necessary to limit the air gap to small values.

It is the principal object of our invention to provide an improved type of magnetron in which 15 the magnetic field is used to its fullest advantage.

In accordance with the invention, the iron core of the magnet is utilized to supply the heating current. A magnetron in which the cathode filament is supported between two opposed leads 20 sealed in opposite ends of the envelope is utilized so that the filament lead-ins terminate in contact pieces received within recesses in the pole pieces of the magnet. The current carrying connections to the filament are provided by the pole 25 pieces. Since the axial length of the envelope need not be greater than that of the electrode system proper, the magnetic airgap can be reduced to practically a minimum.

The novel features which we believe to be characteristic of our invention are set forth with particularity in the appended claims, but the invention itself will best be understood by reference to the following description taken in connection with the accompanying drawing in which the figure in the drawing is a schematic diagram partially in section of a magnetron embodying our invention.

In the drawing the magnetron is provided with an elongated envelope 1 containing a thermionic cathode 2 and two semi-cylindrical anode segments 3 and 4 provided with leads 7 and 8. The straight filament cathode is supported between and terminates in two contacts 5 and 6. The magnetic field is generated by an electro-magnet 45 having a U-shaped core 9 conductively divided in the center so far as carrying an electric current is concerned by means of a thin insulating disc 10, for example fibre. Obviously, the division of the yoke of the magnet by means of an air gap is likewise sufficient, if the structural connection of the two arms or legs is carried out by means of electrically insulating parts. The two arms of the iron core support the winding 11 which can be connected to a direct voltage source 50 at the terminals 12 and 13. Terminals 14 and 15 can be connected to a heating voltage source for supplying the cathode filament. In view of the large iron cross section, no appreciable loss

of heating voltage occurs. Obviously, in place of an electro-magnet, a permanent magnet could be used.

While we have indicated the preferred embodiment of our invention of which we are now aware and have also indicated only one specific application for which our invention may be employed, it will be apparent that our invention is by no means limited to the exact forms illustrated or the use indicated, but that many variations may 10 be made in the particular structure used and the purpose for which it is employed without departing from the scope of our invention as set forth in the appended claims.

What we claim as new is—

1. An electron discharge device comprising an elongated evacuated envelope containing a straight thermionic cathode extending thru opposite ends of said envelope and an anode, magnetic poles positioned close to the ends of said 20 envelope to provide a magnetic field parallel to said cathode, said poles being electrically insulated from each other and connected to opposite ends of the thermionic cathode to serve as current leads for said cathode. 25

2. A magnetron comprising an elongated evacuated envelope containing a straight thermionic cathode extending thru opposite ends of said envelope and a plurality of anodes, contacts on the outside of said envelope connected to said cathode, and a U-shaped discontinuous magnet formed to receive the envelope between its legs recessed for receiving said contacts, the legs constituting conductors for the heating current 30 for said filament. 35

3. A magnetron having an elongated envelope provided with flat ends transverse to the longitudinal axis of the envelope, a straight thermionic cathode extending thru opposite ends of said envelope and provided with contacts at its ends, anodes within said envelope positioned around said thermionic cathode, a U-shaped magnet for providing a magnetic field parallel to said cathode and having oppositely disposed pole faces on the legs of said magnet, said envelope being received between said oppositely disposed pole faces, said faces having recesses for receiving the cathode contacts whereby the envelope is positioned close to the pole faces of said magnet, an insulator electrically insulating the opposite legs of said magnet and terminals on said opposite legs whereby a voltage can be applied to opposite ends of the thermionic cathode thru said legs. 40 45 50 55
